UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 15,506, dated October 28, 1884.

Application filed August 7, 1884. Term of patent 3½ years.

To all whom it may concern:

Be it known that I, LOUISE TULLY, of the city, county, and State of New York, have invented and produced a new and original Design for a Pattern of a Girl's Costume, (numbered 9,328;) and I do hereby declare that the engraved prints accompanying this specification convey to any one accustomed to using paper patterns a clear understanding of how a garment made up by the pattern will appear.

The design shows loose fronts lapped in a curve from the throat to the left hip, a half-fitting back, a box-plaited skirt, a rounding

front drapery displaying draping in its back edges, a full back drapery displaying shirtings below a ruffled heading at the top, coat-sleeves, and a standing collar. 15

What I claim as my invention, and desire to secure by Letters Patent, is—

The design for a girl's costume, as shown 20 in the engraved prints accompanying this specification.

LOUISE TULLY.
